TOY WEAPON

Mahlon Hirsch, Erie, Pa., assignor to Louis Marx & Company, Inc., New York, N. Y., a corporation of New York

Application October 30, 1952, Serial No. 22,053

Term of patent 7 years

(Cl. D34—15)

To all whom it may concern:

Be it known that I, Mahlon Hirsch, a citizen of the United States and a resident of Erie, in the county of Erie and State of Pennsylvania, have invented a new, original, and ornamental Design for a Toy Weapon, of which the following is a specification, reference being had to the accompanying drawing, forming a part thereof, wherein:

Fig. 1 is a side elevation of a top weapon embodying my new design;

Fig. 2 is a plan view of the same;

Fig. 3 is an end view, looking at the muzzle end of the same;

Fig. 4 is a side elevation similar to Fig. 1, but showing the opposite side of the weapon;

Fig. 5 is a bottom view; and

Fig. 6 is an end view, looking at the breech end of the same.

I claim:

The ornamental design for a toy weapon, substantially as shown.

MAHLON HIRSCH.
